PEDAL ACTION UNIT FOR PIANOS

Harry C. Kaprelian, 320 Pearl St.,
Kingston, N.Y. 12401

Filed July 6, 1971, Ser. No. 160,241

Term of patent 14 years

Int. Cl. D17—01
U.S. Cl. D56—9

FIG. 1

FIG. 3

FIG. 1 is a top plan view of a pedal action unit for pianos, showing my new design;

FIG. 2 is a bottom plan view; and

FIG. 3 is a side elevation view, the opposite side being substantially a mirror image thereof.

I claim:

The ornamental design for a pedal action unit for pianos, substantially as shown and described.
